UNITED STATES PATENT OFFICE.

LUCIUS A. LINDSEY, OF ARMUCHEE, GEORGIA.

THERMOSTAT.

1,052,674.

Specification of Letters Patent. Patented Feb. 11, 1913.

Application filed December 14, 1911. Serial No. 665,720.

To all whom it may concern:

Be it known that I, LUCIUS A. LINDSEY, a citizen of the United States, residing at Armuchee, in the county of Floyd and State of Georgia, have invented certain new and useful Improvements in Thermostats; and I do declare the following to be a full, clear, and exact description of the invention, such as will enable others skilled in the art to which it appertains to make and use the same.

This invention relates to electric signaling, and more especially to thermal circuit closers; and the object of the same is to produce an improved type of thermostat which will actuate the circuit closer when the temperature changes rapidly but which will not do so when the change of the temperature is more deliberate.

To this end the invention consists in so constructing the thermostat and connecting its parts with the signal that a sudden change in the temperature will actuate the former which in turn will actuate the latter, whereas a more deliberate change in temperature will not do either.

The invention also contemplates the provision of a safety appliance whereby an excessive rise in temperature, even though the rise be gradual, will actuate the alarm.

One embodiment of my invention is described in the following specification and shown in the accompanying drawings wherein—

Figure 1 is a general side elevation of this device, showing the circuits and alarms in diagram. Fig. 2 is an enlarged vertical section through the thermostat alone, and Fig. 3 is a cross section on the line 3—3 of Fig. 2.

In the drawings I have purposely shown my invention as applied to and used in connection with an electric circuit closer so that the action of the thermostat may be communicated to a distant point where it will sound an alarm or actuate a signal, because this is probably the most practical embodiment of the idea; but I desire it to be understood that I do not wish to be limited to a restricted use of the invention because I consider the latter as broad as the language of the broadest claim.

The numeral 1 designates an envelop entirely surrounding and inclosing a drum 2 so as to leave an air space or jacket 3 between them. The envelop and drum are

preferably made of light sheet metal such as copper, and their size and shape is immaterial although by preference they are globular and the inner member 2 stands concentric within the outer member 1 so that the air jacket 3 is of one width throughout, excepting opposite the diaphragm described below. These two members are connected at one point in any suitable manner as by a tube 4 whose extremities are secured to the two members so as to hold them rigidly in their proper relative position and yet not admit air to the jacket 3, and within this tube in the present embodiment of my invention is insulation 5 through which passes a rod 6 having a point 7 at its inner end, a wire 8 connected with its outer end and led to some suitable point, and adjusting means 9 for varying its position within the insulation, the specific character of said means being immaterial. In the illustration I have shown the insulation 5 as being a nut through which the rod 6 screws, and the member 9 as a head on the outer end of the rod so that the latter may be turned to adjust its position, and this I have done merely for purposes of illustration. At a point directly opposite the tube 4 the outer member or envelop 1 carries an outwardly projecting nipple 14 also containing insulation 15, and through the latter passes another rod 16 having a point 17 at its inner end, a wire 18 leading from its outer end to a suitable point, and adjusting means 19 of any suitable type. Here again the means for adjusting the position of the rod 16 and its point 17 are illustrated as the same as the means employed for adjusting the rod 6 and its point 7, although simply for sake of illustrating one adjusting means. If the concentric members 1 and 2 be globular or spherical as shown, the two rods 6 and 16 will pass through its diameter and will stand in true alinement, and their points 7 and 17 are slightly spaced for a purpose which will appear.

One side of the inner member or drum 2 is cut off as seen in the drawings, and the edges of the opening thus left are connected by a diaphragm 20 preferably having concentric corrugations 21 in its body and a button 22 at its center, this diaphragm being also of thin metal, or of fabric rendered air tight in some suitable manner, and closing the interior of the drum 2 so as to maintain the jacket 3 within the envelop 1

air-tight. Leading from the diaphragm if it be of metal is a wire 28 which is carried through insulation 29 in the envelop 1 to a suitable point, and if the diaphragm be of a material which is a non-conductor of electricity, this wire will lead from the button 22 as will be clear.

For purposes of illustration I have shown one manner in which this improved 10 thermostatic may be connected electrically with two alarm bells, although this system of wiring is the arrangement which I prefer and may be replaced by others.

The wire 18 from the pin 16 leads through 15 a switch or circuit breaker 30 and thence through the coil of a relay 31 and to one pole of a battery 32, and the other pole of the latter is connected by wire 28 with the button 22 on the diaphragm. It follows 20 that when said button is in contact with the point 17 of the rod 16, the circuit flows through the coil of the relay and the armature 33 is attracted so that contact is broken between it and a point 34 which is connected 25 with one pole of a bell 35. The other pole of the latter is connected by a branch wire 36 with the wire 28 at the opposite side of the battery 32, and it follows that when contact between the button 22 and point 17 is 30 broken and the relay magnet is deenergized its armature 33 reestablishes contact with the point 34 and a local circuit is set up through the battery and bell and the latter is sounded. In some cases this signal alarm 35 might be considered sufficient, but I propose to make use generally of a second alarm for the sake of greater security. One pole of the bell 37 thereof is connected by a wire 38 which joins the wire 18 at one side of the 40 battery 32, the other side thereof being connected with the button 22 by the wire 28 as above described; and the other pole of said bell is connected with the wire 8 leading to the rod 6 and point 7, a switch or circuit breaker 39 being by preference interposed in 45 this wire 8. When this switch is open this alarm circuit is cut out; and on the other hand when the switch 30 is open the alarm circuit above described is cut out, or both 50 switches may be opened at times if desired.

The parts being assembled about as shown in the drawings, the action of my device will now be apparent. Air is of course trapped within the drum 2, and another stratum of 55 air within the air space or jacket 3 around the drum 2 and within the envelop 1, and outside the latter is the air in the apartment containing this thermostat which is preferably supported therein remote from 60 the walls and windows in any suitable way, as by the eye 40. Assuming now that a fire occurs within the apartment. The temperature of the air therein rises rapidly and heats the shell of the envelop 1 so that the 65 air within the air space 3 is slightly warmed

and therefore expands, but the air within the drum 2 has not yet been heated and therefore does not expand. The expanding air within the envelop 1 outside the diaphragm cannot escape, and its pressure on 70 the diaphragm will therefore move the same to the left or inward so that its button 22, which normally stands in contact with the point 17 as shown in Fig. 2, is moved away from the same, and the circuit through the 75 coil of the relay is interrupted and the alarm 35 is sounded in the manner above described. Assuming, however, that this alarm should fail to work and yet the temperature continues to rise rapidly. The further movement of the button 22 at the center of the diaphragm to the left will soon throw it into contact with the point 7, and then a circuit is completed through the bell 37 and the other alarm is sounded. If, however, the temperature of the air within the apartment 80 changes slowly, the change is communicated through the shell of the envelop 1, to the air within the air space 3 and by it to the shell of the drum 2, and thence through the latter to the air contained within this drum; and the result is that the temperature of the air on opposite sides of the diaphragm will not vary to any material extent and therefore the pressure on opposite sides of the diaphragm will not differ materially. By 85 adjusting the two rods 6 and 16 their points 7 and 17 may be set with respect to the button 22 in such a way that the diaphragm will be permitted to flex slightly 90 without causing the button to move out of contact with the point 17 or into contact with the point 7, and yet a sudden rise in temperature will sound first one alarm and 95 then the other, or both alarms if they are 100 both in working order.

On extremely rare occasions it occurs that a fire starts and burns so slowly that the heat rises very deliberately, and as it is possible in such event neither alarm above described would be sounded I make use of the following means for sounding an alarm when excessive heat is reached whether it be reached quickly or slowly: The outer envelop 1 is by preference made in two cup-shaped halves or parts which are connected in an air-tight manner by a fusible joint 41, and the line of division across the sphere shown in the drawings is indicated as oblique so that when excessive heat melts this joint and the right hand portion of the envelop falls away from the left hand portion the point 17 connected with the wire 18 will 110 positively be removed from the button 22 connected with the wire 28 and the circuit through the relay will be broken whether the diaphragm be deflected or not. I prefer to divide the globular envelop on an oblique line so that the weight of the right and lower part tends to draw it away from the 115 120 125 130

left and upper part which is here supported at the point 40, and thereby use gravity to assist in breaking the circuit in times of necessity.

5 I have not considered it necessary to illustrate in the drawings the fact this device might also be employed for sounding an alarm on the occasion of a sudden fall in the temperature, although it is possible to use 10 the thermostat in that way as when it is located within an apartment containing incubators. A mere reversal of the circuits illustrated in Fig. 1 and a setting of the point 7 in contact with the button 22 would be one means for carrying out this idea. Thereafter any sudden fall in temperature would cause a decrease of the volume of air within the space 3 and a deflection of the diaphragm away from the point 7, and the 15 result would be the same as above indicated for a sudden rise in temperature. It is also possible by a modification of the wiring and the circuits to adapt this device to sound an alarm on either the sudden rise or the sudden fall of temperature, and this also will be 20 well understood without further description or illustration.

What is claimed as new is:

1. The herein described thermostat comprising a drum whose shell has an opening, a flexible diaphragm across said opening and trapping air within the drum, an air tight envelop of heat-conducting material inclosing said drum and diaphragm so as to 30 form an air jacket between them and the envelop, and circuit devices within the drum actuated by the movements of said diaphragm and leading to the exterior of said envelop.

40 2. The herein described thermostat comprising a drum whose shell has an opening, a flexible diaphragm across said opening and trapping air within the drum, an air tight envelop inclosing said drum and diaphragm so as to form an air jacket between them and the envelop, a tube rigidly connecting the latter with the drum, insulation within said tube, a metal rod passing through said insulation with its point adjacent said 45 diaphragm, and wires connected with the diaphragm and rod for the purpose set forth.

3. The herein described thermostat comprising a drum whose shell has an opening, a flexible diaphragm across said opening and trapping air within the drum, a button at the center of the diaphragm, an air tight envelop inclosing said drum and diaphragm so as to form an air jacket between them 55 and the envelop, means for rigidly connecting the latter with the drum at a point in line with said button, a rod extending through the connecting point with its inner end adjacent the button, a nipple in the envelop diamet- 60 rically opposite said rod, a second rod ex-

tending through the nipple with its point opposite the other side of the button, means for adjusting the position of both rods, and wires leading from the rods and the button.

4. The herein described thermostat comprising a drum whose shell has an opening, a flexible metallic diaphragm across said opening and trapping air within the drum, an air tight envelop inclosing said drum and diaphragm so as to form an air jacket between them and the envelop, means for rigidly connecting the latter with the drum, a rod extending through the connecting point, a nipple in the envelop diametrically opposite said rod, a second rod extending through the nipple with its point opposite the other side of the diaphragm, means for adjusting the position of both rods, wires leading from said rods, and a third wire leading from the diaphragm through and 85 insulated from the shell of the envelop.

5. A thermostat consisting of a globular envelop of heat-conducting metal divided on an oblique line into two parts, a fusible joint connecting said parts so as to render 90 the envelop air-tight, means for supporting one part above the line of division so as to permit the other part to fall away from it when the joint is melted by heat, a diaphragm contained within said envelop, 95 means for flexing it by sudden changes in temperature, and means for sounding an alarm when the diaphragm is moved; combined with an electric alarm whose terminal wires are connected with said parts and through the fuse joint with each other so as to produce a closed circuit which is broken by the movement of the last-named part away from the other after the joint has been melted, the breaking of said circuit sounding an alarm.

6. A thermostat comprising two concentrically disposed air-containing members whose shells are of heat conducting material, that of the outer member being divided on an oblique line into two parts, a fusible joint connecting them, means for suspending the uppermost from an overhead support, the shell of the inner member having an opening, and a flexible diaphragm across 110 said opening and closing communication between the chambers within said members; combined with a button at the center of said diaphragm, a wire connected with the button and leading to the exterior of the outer member, a rod mounted through the lower part of the outer member with its point directed toward said button, a second rod mounted through the upper part of this member and through the wall of the inner member with its point directed toward the opposite side of said button,

wires leading from both said rods, an alarm in circuit with the low-rod-wire and said wire from the button; and a second electric 115 120 125 130

alarm whose terminal wires are connected with said parts and through the fuse joint with each other so as to produce a closed circuit which is broken by the movement 5 of the last-named part away from the other after the joint has been melted, the breaking of said circuit sounding an alarm.

7. A thermostat comprising two concentrically disposed air-containing members 10 whose shells are of heat conducting material, that of the outer member being divided on an oblique line into two parts, a fusible joint connecting them, means for suspending the uppermost from an overhead support, 15 the shell of the inner member having an opening, and a flexible diaphragm across said opening and closing communication between the chambers within said members; combined with a button at the center of 20 said diaphragm, a wire connected with the button and leading to the exterior of the outer member, a rod adjustably mounted

through the lower part of the outer member with its point directed toward said button, a second rod adjustably mounted through 25 the upper part of this member and through the wall of the inner member with its point directed toward the opposite side of said button, wires leading from both said rods, an alarm in circuit with the low-rod-wire 30 and said wire from the button and including a battery, a relay, and a bell on a branch circuit through the relay armature; and a second alarm in circuit with the upper-rod-wire and the button-wire and including said 35 battery and a bell.

In testimony whereof I have hereunto set my hand in presence of two subscribing witnesses.

LUCIUS A. LINDSEY.
